United States Patent Office.

BENJAMIN MOSER, OF BROOKLYN, NEW YORK.

Letters Patent No. 85,842, dated January 12, 1869.

IMPROVED CURTAIN-FIXTURE.

The Schedule referred to in these Letters Patent and making part of the same.

To all whom it may concern:

Be it known that I, BENJAMIN MOSER, of Brooklyn, in the county of Kings, and State of New York, have invented a new and improved Window-Shade Fixture; and I do hereby declare that the following is a full, clear, and exact description thereof, which will enable others skilled in the art to make and use the same, reference being had to the accompanying drawings, forming part of this specification.

Figure 1 represents a front view of my improved window-shade fixture.

Figure 2 is a vertical transverse section of the same, taken on the plane of the line $x z$, fig. 1.

Similar letters of reference indicate corresponding parts.

The object of this invention is to so arrange the apparatus for adjusting window-curtains that the roller cannot only be readily turned to wind or unwind the curtain, but that it can also be adjusted higher or lower, as may be desired, to have the curtain opposite any desired part of the window. The roller can be turned when it is high or low.

The invention consists in the arrangement of parts, as will be hereinafter more fully described.

A, in the drawing, represents a suitable window-frame.

B is the shade-roller.

C, the shade.

Around the ends of the roller B are loosely fitted two sleeves, a a' , which are suspended by means of ropes D E, respectively, from pulleys b d , that are also fitted to the frame A.

The cord D is fastened to one sleeve, a , passes over the top roller c , then down towards and over the lower roller d , and has its other end then also fastened to the sleeve a .

The other cord, E, is fastened with one end to the

other sleeve, a' , passes then over the pulleys b and c , as shown, and is finally either fastened to the other rope, D, or fitted around d , and secured to the sleeve a .

The roller B is thus suspended in the sleeves a a' , and can be raised and lowered by moving the cords D E together in the desired direction. Within these sleeves the roller can freely.

F is an endless cord fitted around two rollers e and f , as shown, and coiled once around the roller B, as in fig. 2. It will, when it is pulled, cause the shade-roller to revolve in its supports a a' , thereby winding or unwinding the curtain.

One of the rollers, c or d , should be up-and-down adjustable, to keep the cords D E always tense. Thus, by means of the ropes D E, the roller can be raised or lowered at will, so as to bring the shade opposite any desired part of the window. Thus, for example, the upper part of the window can be left open, as shown, and only the lower part or the middle covered.

By means of the cord F, the curtain can be wound around or unwound from the roller, in whatever position the latter may be.

Having thus described my invention,

What I claim as new, and desire to secure by Letters Patent, is—

The arrangement of the cords D E, passing around the pulley d , and secured to the curtain-sleeve a , in combination with the pulleys c b , curtain-sleeve a' , and the cord and pulleys F e f , as herein described, for the purpose specified.

The above specification of my invention signed by me, this 18th day of August, 1868.

BENJAMIN MOSER.
